FOLLOW-UP SYSTEM

James M. Boyle, Darien, Conn.

Original application December 16, 1939, Serial No. 309,589. Divided and this application February 20, 1942, Serial No. 431,647

1 Claim. (Cl. 172—293)

(Granted under the act of March 3, 1883, as amended April 30, 1928; 370 O. G. 757)

The invention herein described may be manufactured and used by or for the Government of the United States for governmental purposes without the payment to me of any royalty thereon in accordance with the provisions of the act of April 30, 1928 (ch. 460, 45 Stat. L. 467).

This invention relates to electrical follow-up mechanisms especially of that type suitable for use in an arrangement wherein an ampere hour or kilowatt hour meter is located at a point remote to additional meter dials, whereby the remote meter dials are caused to move by the intervention of electrical conductors. However, the invention is not to be understood as being limited to use in such a system.

This application is a division of my application Serial No. 309,589, filed December 16, 1939 (Patent No. 2,273,829, February 24, 1942).

The principal object of this invention is to provide a follow-up mechanism for moving meter dials or other indicating mechanism located at a point remote from a primary control system.

Another object of this invention is to provide a signal device for indicating when a follow-up mechanism is operating.

Other and further objects of the invention will appear from the specification hereinafter following when read in connection with the accompanying drawing, in which

Fig. 1 is a diagrammatic representation of the invention showing certain parts partially in section; and

Fig. 2 is a plan view of the circuit opening and closing arrangement associated with the cycling motor shown in Fig. 1.

In Figs. 1 and 2, a shaft 1 is the controlling shaft which when turned any number of revolutions produces an equivalent movement of a controlled mechanism. The shaft 1 through a worm gear arrangement turns the insulated gear wheel 2 upon which is mounted a segmental contacting face 3. By the proper selection of the gearing, the gear wheel 2 can be arranged to rotate once for every increment of motion that it is desired to impart to the controlled mechanism. Where the present mechanism is used for driving a remotely situated electric meter, for instance, the gear 2 can be arranged to rotate once for every 50 or 100 watt hour of energy passing through the meter, or once for a predetermined number of ampere hours of current, so that at each half revolution the contacting face 3 will pass under and metallically connect the brush contacts 4 and 5 and later the brush contacts 6 and 7. The apparatus just described and the signal lamp 8 are

located at the controlling station. In an electric metering system this would be in the outside meter box mounted on a power pole or elsewhere, while the controlled station is at a different location. Brush contacts 5 and 7 are connected together and to a source of electric potential at 9. Contact 6 is connected via conductor 10 to one terminal of the signal light 8. The other terminal of the signal light 8 is connected to the source of potential at 9. Contact 4 is connected by way of auxiliary conductor 11 to the brush 12 at the controlled station. The contact 6 is connected by conductor 13 to the brush 14 at the controlled station. The brushes 12 and 14 are mounted on opposite sides of the shaft 15 so as to contact the partially complete circular slip rings 16 and 17, respectively, insulatingly carried on the disc 18 mounted on shaft 15 of electric cycling motor 22. Also insulatingly carried on the disc 18 is a complete circular slip ring 19 which has a brush 20 bearing thereagainst. The brush 20 is connected by way of conductor 21 to one terminal of the motor 22. The other terminal of the motor 22 is connected to ground at 23. The slip ring 19 is connected via conductor 23 to the slip ring 16 and also via conductor 24 to the slip ring 17.

The friction wheel 25 engages the surface of disc 18 and also the surface of disc 26 which is drivingly connected with the counting mechanism 27. The counting mechanism 27 and disc 26 are mounted for movement axially of the shaft carrying friction wheel 25, so that the counter 27 may be so adjusted in position that any increment of motion of shaft 1 will cause a proportionate desired increment of motion of the counter. The operation of the system is as follows: the shaft 1 upon rotating, drives gear 2 to effect the alternate closing of circuits between contacts 4 and 5, and then contacts 6 and 7 by means of the segmental contacting face 3 mounted on gear 2. Each time a circuit is closed between contacts 4 and 5 at the controlling station a circuit is closed for the motor 22 located at a remote point to cause this motor to drive the disc 18 one-half of a revolution by the following circuit: source of potential 9, contact 5, segment 3, contact 4, conductor 11, brush 12, incomplete slip ring 16, conductor 23, slip ring 19, brush 20, conductor 21 to the motor 22 and from thence to ground. Upon completion of the above-traced circuit, the motor 22 revolves turning disc 18 one-half revolution, or until the incomplete slip ring 16 leaves the brush 12 opening the circuit of motor 22. As the shaft 1 turns further

a circuit is ultimately made between contacts 6 and 7 by way of the segment 3, whereupon the motor 22 once more turns the disc 18 one-half revolution via the following circuit: source of potential 9, contact 7, segment 3, contact 6, conductor 13, brush 14, incomplete slip ring 17, conductor 24, slip ring 19, brush 20, conductor 21, motor 22 and thence to ground, whereupon the motor 22 revolves, driving the disc 18 for a half revolution, or until the circuit is opened at brush 14 when the cut-out or incomplete portion of slip ring 17 comes opposite thereto. It is thus evident that each time the gear 2 driven by shaft 1 makes a half revolution the disc 18 likewise makes a half revolution. The disc 18 when turning, drives the meter dials or counting mechanism 27 through the friction disc by means of the friction wheel 25 and disc 26, causing the counter or meter 27 to be driven an amount proportional to the movement of shaft 1 or shaft 15.

The turning of the shaft 1 and disc 2 causes the lamp 8 to be lighted each time the segment 3 bridges contacts 6 and 7 to indicate that the shaft 1 is turning. In a remote meter controlled arrangement such as that disclosed in my application Serial No. 309,589, filed December 16, 1939, this lamp is preferably placed in such a position that line attendants can, by the flashing thereof, check the operation of the meter.

In the description the signalling motor 22 has been referred to as an electric motor. This motor may be of such a type as to be driven by alter-

nating current or direct current. For reasons of economy in a meter system the motor 22 is preferably made as a very small motor with a reduction gear connection between the motor shaft proper and the shaft 15. However, this is not a necessary requirement in all cases.

It will be obvious that this invention is not limited to the means shown, and that equivalent means may be employed without departing from the spirit of the invention.

I claim:

A follow-up mechanism for moving a controlled shaft in response to movement by a controlling shaft comprising at least two pairs of contacts with means for cyclically closing said contacts responsive to rotation of said controlling shaft, a plurality of interconnected slip rings at least two of which are discontinuous, carried by said controlled shaft, a brush adapted to contact with each of said slip rings, means for electrically connecting each of the brushes associated with said discontinuous slip rings with respective contacts of said pairs of contacts, means electrically connecting the remaining contacts of said pairs of contacts to a source of potential, means connecting the brush associated with said continuous slip ring with a motor for driving said controlled shaft, whereby said motor acts to move said controlled shaft responsive to the closure of said contacts by movement of said controlling shaft.

JAMES M. BOYLE.
